UNITED STATES PATENT OFFICE.

CHARLES D. BENNETT AND WILLIAM M. DALY, OF KIRKWOOD, MISSOURI.

DESIGN FOR A PUMP-CURB.

SPECIFICATION forming part of Design No. 25,014, dated December 24, 1895.

Application filed July 29, 1895. Serial No. 557,509. Term of patent 14 years.

To all whom it may concern:

Be it known that we, CHARLES D. BENNETT and WILLIAM M. DALY, of the city of Kirkwood, St. Louis county, State of Missouri, have invented a new and original Design for a Pump-Curb, of which the following is a full, clear, and exact description, reference being had to the accompanying drawing, forming a part hereof.

10 In the drawings the view is a side elevation of a pump-curb embodying our design.

The leading feature of our design is a hollow body or casing constructed with opposite parallel vertical sides and an upper side in 15 form of a semicircle and a lower side in the form of a compound curve, the base whereof projects downwardly on one side a greater distance than on the opposite side.

11 indicate two circular bases which are 20 surmounted by rectangular bodies 2.

3 indicates a short vertical cylinder surmounting one of said rectangular bodies 2, and 4 indicates another vertical cylinder which surmounts the other one of said rectangular bodies 2.

5 indicates the body or casing, the same being constructed with parallel sides 6, cylindrical portions 7 depending from the under side of said body and surmounting the upper ends of the said cylinders 3 and 4. The under side 8 of said casing is in the form of a compound curve, while the upper side 9 thereof is in the form of a semicircle. Extending around the body or casing 5 is a series of ornamental bands 10, from which project small 35 lateral bodies 11.

Extending laterally from one of the cylindrical portions 7 is a cylindrical projection 12, the outer end of which is turned downwardly.

40 We claim—

The design for a pump-curb as herein shown and described.

In testimony whereof we affix our signatures in presence of two witnesses.

CHARLES D. BENNETT,
WILLIAM M. DALY.
